UNITED STATES PATENT OFFICE

HORACE T. DE LONG AND JOHN W. HYER, OF GRAND JUNCTION, COLORADO

ATTACHMENT FOR COTS OR THE LIKE

Application filed April 8, 1929. Serial No. 353,493.

The present invention is directed to improvements in attachments for cots or the like.

The primary object of the invention is to provide an attachment so constructed that it can be conveniently attached to a cot or the like and, when in place, will serve to retain heat and exclude cold from the top of the cot.

10 Another object of the invention is to provide a device of this kind constructed in such manner that the crossed supporting legs of the cot will not rumple or distort the casing in order that the maximum capacity 15 of the compartments of the casing will be utilized for retaining heat and excluding cold.

Another object of the invention is to provide a device of this kind which can be 20 easily and quickly attached to or removed from the cot, as desired.

Another object of the invention is to provide a device of this kind which is so constructed that it will not interfere with folding of the cot.

With these and other objects in view, this invention resides in the novel features of construction, formation, combination and arrangement of parts to be hereinafter more 30 fully described, claimed and illustrated in the accompanying drawings, in which:

Figure 1 is a perspective view of the cot showing the device in place thereon.

Figure 2 is a transverse sectional view.

35 Figure 3 is a longitudinal sectional view.

Figure 4 is a perspective view of the attachment.

Figure 5 is a sectional view on the line 5—5 of Figure 2.

40 Figure 6 is a fragmentary sectional view showing a slightly modified form of the invention.

Referring to the drawings, the numeral 1 designates a folding cot which includes side 45 rails 2 and end rails 3. To the side rails 2 are secured the upper ends of the end legs 4 and the upper ends of the intermediate legs 5, said legs being crossed and pivotally connected, as at 6. Supported by the side 50 and end rails, as is customary, is the fabric

top 7. The construction thus far described is of the well known type.

Detachably secured to the cot is a casing 8 which includes a bottom 9, sides 10, ends 11 and a top 12 which define a compartment 13 substantially of the same width and length as the cot. The sides 10 terminate at their upper ends in flaps 14 having carried thereby a plurality of snap sockets 15, the purpose of which will be later explained. 60

The casing 8 is formed from canvas or other suitable fabric and the sides 10 thereof are provided with centrally disposed gussets 16 to accommodate the legs 5 so that the casing will retain its rectangular formation 65 when the cot is in use.

Fabric strips 17 are provided and are tacked upon the side rails 2 and have thereon a plurality of heads 18 which cooperate with the sockets 15 to secure the casing below 70 the top 7 of the cot. The top 12 of the casing will be maintained spaced from the top 7 of the cot to provide an additional compartment 19.

It will be obvious that when a person is 75 occupying the cot warmth from the body will be transmitted to the compartments 13 and 19 and will be retained therein, and the cold excluded and prevented from reaching the top 7. Since heat will be retained and 80 cold excluded, the cot can be used without a mattress or pad.

While the device is illustrated in connection with a cot of conventional form it will, of course, be understood that it is equally well 85 adapted for use in connection with various types of beds or cribs.

From the foregoing, it is thought that the construction, operation and many advantages of the herein described invention will be apparent to those skilled in the art, without further description, and it will, of course, be understood that various changes in the size, shape, material and proportion and minor details of construction may be resort to without departing from the spirit or sacrificing any of the advantages of the invention. 95

As shown in Figure 6, the ends 11 have flaps 20 carried thereby for detachable en- 100

gagement with the end bars 3. It will, of course, be understood that we do not wish to be limited to the number of compartments. If desired, the bottom 9 and top 12 can be 5 connected by cords or webs to prevent sagging of the bottom 9.

Having thus described the invention, what is claimed is:

1. In a device of the class described, the 10 combination of a cot, a fabric casing forming a compartment for disposition under the top of the cot, the sides of the casing having gussets therein for accommodating certain legs of the cot.
- 15 2. In a device of the class described, the combination of a cot including a top and crossed supporting legs, a fabric casing defining a compartment, the sides of the casing having flaps carried thereby for detachably 20 engaging the side rails of the cot, the top of the casing being spaced from the top of the cot to provide an additional compartment, the sides of the casing having gussets carried thereby for accommodating certain legs 25 of the cot when the cot is in its operative position.
- 30 3. In a device of the class described, the combination with a cot and its supporting legs, of a fabric casing forming a compartment below the cot and shaped at the sides to accommodate certain of the legs of the cot, strips fixed to the side rails of the cot, securing flaps extending from the sides of the casing, and fastening devices removably securing said flaps to said strips.

In testimony whereof we affix our signatures.

HORACE T. DE LONG. [L. S.]
JOHN W. HYER. [L. S.]
